UNITED STATES PATENT OFFICE.

JACOB GREENWALD, OF PHILADELPHIA, PENNSYLVANIA, ASSIGNOR TO GREENWALD BROTHERS, INCORPORATED, OF PHILADELPHIA, PENNSYLVANIA, A CORPORATION OF PENNSYLVANIA.

DRAWERS.

No. 907,593.

Specification of Letters Patent. Patented Dec. 22, 1908.

Application filed July 8, 1908. Serial No. 442,456.

To all whom it may concern:

Be it known that I, JACOB GREENWALD, of Philadelphia, in the county of Philadelphia and State of Pennsylvania, have invented 5 certain new and useful Improvements in Drawers, whereof the following is a specification, reference being had to the accompanying drawings.

The most obvious application of my invention is for use in connection with ordinary bathing trunks, and I have therefore shown it as thus embodied.

In the drawings, Figure I, represents a view in perspective of a pair of bathing trunks containing my invention, showing the garment in the adjustment which it would have when worn. Fig. II, is an enlarged partial view of one side of the waist region, showing the periphery of the waist extended 10 as it would be when the garment is about to be put on, or taken off.

The object of my invention is to construct a garment of this character in which the necessary close and elastic fit for clinging to the 15 waist can be obtained by the use of a short and comparatively strong elastic band or bands. As heretofore made, such garments have usually either been provided with an ordinary drawing-string, or else with an 20 endless rubber band which encircled the entire waist. Both of these devices are objectionable, the drawing-string being non-elastic, and the endless band at the waist being usually either too weak to adequately 25 support the garment upon the wearer, or else, if strong enough to be efficient, occasioning difficulty in putting it on and taking it off. By my invention, the difficulties referred to are overcome.

10 In the drawings, 1, represents a pair of bathing trunks, having a deep welt, or hem 2, at the waist. At a convenient region or regions of the waist, preferably two in number, as indicated at 3, 3, I form openings in 15 the welt, as shown at 4, 4. Within each of the inclosures or elongated pockets thus formed, is freely contained a short and very strong elastic band 5, preferably of flat rubber tape, which is preferably free at both 20 ends as shown. The free ends are provided with detachable fastening devices, these in the instance shown, being ordinary glove fastener sockets 6, adapted to engage with

studs 7, which latter are secured to the exterior of the welt 2, just beyond the openings 4, 4, so that the elastic band can be detached at either or both of its ends.

The fullness of the waist line and the length of the elastic band are such that when the waist is stretched or extended, and 60 the bands are unfastened at one end, for instance, the free ends will be drawn well within the inclosure of the welt. To avoid the "loss" of the end thus drawn into the inclosure, I attach to each free end of the 65 band a cord or finder 8, so that the end of the band which has disappeared within the welt, can readily be drawn out again. In the instance shown, the two bands are located at diametrically opposite regions of 70 the waist band, at points which would be adjacent to the hips of the wearer, but this location can of course, be varied, and, if desired, one of the bands might be omitted. Obviously, also the desired inclosure for the 75 bands might be provided otherwise than by utilizing the waist welt for that purpose.

In the use of the device, when the garment is about to be put on, one end of each band 5, is detached from its fastener, and the 80 waist band is then freely extended so that the wearer can readily slip the garment on. The ends of the elastic bands which have disappeared within the welt are then drawn out by means of the finders 8, and the socks 85 of the fasteners are snapped upon the studs, whereupon, the elasticity of the rubber will cause the garment to cling with the necessary degree of tightness to the waist of 90 the wearer, and the fabric at the regions of 90 the gusset will be gathered, as indicated in Fig. I.

In order to remove the garment, the rubber bands are freed at one end, whereupon, the waist of the garment can be stretched to 95 the full extent without difficulty.

I prefer to make the bands detachable at both of their ends, in order that the garment may be worn with either part of the waist in front, as it is easier to detach and draw the 100 front end of the band than the rear one.

By the use of the above device, I am enabled to employ elastic bands of such strength as would not be convenient or comfortable for use if they were not detachable 105 during the act of putting on or taking off,

and moreover, the objections to the use of rubber bands extending around the entire waist are avoided.

Having thus described my invention, I claim:—

1. In a garment of the character described, the combination of a relatively short and strong band of elastic material, arranged within an inclosure at the waist region, said 10 band having a free end; a detachable fastening device arranged at the free end of said band; and a finder connected with the free end of said band.
2. In a garment of the character described, 15 the combination of a pair of relatively short

and strong bands of elastic material arranged within inclosures at the waist region and free at their respective ends; detachable fastening devices arranged at each end of said bands; and finders connected with the respective ends of each band, substantially as set forth.

In testimony whereof, I have hereunto signed my name, at Philadelphia, Pennsylvania, this seventh day of July, 1908.

JACOB GREENWALD.
